UNITED STATES PATENT OFFICE.

CLARENCE E. REED, OF HOUSTON, TEXAS.

DEEP-WELL-DRILLING APPARATUS.

Application filed January 27, 1922, Serial No. 532,130. Renewed September 26, 1923.

To all whom it may concern:

Be it known that I, CLARENCE E. REED, a citizen of the United States, and resident of Houston, Texas, have invented certain 5 new and useful Improvements in Deep-Well-Drilling Apparatus, of which the following is a specification.

This invention consists in the features and combination and arrangement of parts 10 hereinafter described and particularly pointed out in the claims.

In the accompanying drawings

Figure 1 is a side diagrammatic view 15 of a deep well drilling head.

Fig. 2 is a cross section plan view.

Fig. 3 is side-view of the hanger which supports the rotary cutters.

Fig. 4 is a bottom plan view of the hanger of Fig. 3.

20 Fig. 5 is a view of one of the bushings detached.

Fig. 6 is a view of one of the collars.

The drill head comprises a lower main 25 part 1 and an upper screw threaded tapered shank 2 adapted to fit, for instance, into a correspondingly threaded socket of a reamer block between the said head and the drill stem.

The main part of the head is recessed 30 at 3 to receive the hanger 4 upon which the cutters are journaled.

The head is also provided with lateral 35 openings at 5. The cutters 6 protrude from the head through these openings to do the cutting.

As shown the shape of the main part 1 of the head provides jaws 1' 1" between which the cutters and their holding or carrying hanger member 4 are disposed. These 40 jaws house the inner sides or edges of the cutters while the diametrically opposite sides or edges of said cutters, as before stated, protrude from the head. The cutters are offset in relation to each other and in relation to that diameter of the head 45 which is parallel to the cutter axes and they are mounted on cylindrical journal studs 7 integral with the hanger or support 4. This hanger at its lower end consists of a flat plate, the vertical edges 4" of which find bearings against the flat inner surface 1^a of the jaws 1' 1" of the main part of the head. The shoulders or ends 7^a of the journal studs 7 find bearings 50 against the flat inner surface 1^b of the jaws

of the head. By these bearings the hanger is held firmly within the head when seated, and furthermore, additional seating for the hanger is afforded by reduced extensions 8 of the studs 7 which are provided with 60 heads 8^a. The stud extensions 8, fit in notches 9 in the lower edges of the jaws 1' 1" and the heads 8^a of these stud extensions fit in recesses 9^a or enlargements of the notches. The notches are open downwardly and in order to insert the hanger with the cutters into place it is only necessary that it be positioned so that its stud extensions 8 will register with the notches and then the hanger is slipped into the head. 65 The stud extensions enter the notches and the heads of the stud extensions lie countersunk in the recesses of the head and are not subject to the wear that they otherwise would be subjected to, if they extended out 70 beyond the outer surface of the head.

The removable hanger for the cutters has a shank 10 of cylindrical form which fits in a corresponding bore of the head. The upper end of the shank is reduced at 11, 80 and a nut 12 on this threaded part bearing on top of the shank of the head draws the shank up into place with its shoulder 13 bearing on a corresponding shoulder of the head. The lower plate portion of the 85 hanger has inclined edges 14 which come opposite corresponding inclined surfaces at the top of the recess in the head. When the hanger is in place it is held rigidly against movement and is sustained by its 90 shank and by contact with the walls defining the recess in the head. There is space left at 15 around the upper reduced end of the shank of the hanger, and into this space lubricant is fed through a port 95 16 formed through the screw threaded shank of the head, and this port connects with any suitable conduit leading from a reservoir through a part or member, such as a reamer cutter supporting block, with which the said 100 shank connects.

This lubricant is led from the chamber 15 through conduit 17 in the shank of the hanger to the lower part of the hanger where it connects with a cross conduit 18 leading at an angle through the journal studs and to the interior of a bushing 19 interposed between the journal stud and the cutter. This conduit may extend otherwise than at the angle shown. The bush- 110

ing 19 has a recess 20 forming an oil pocket from which the oil passes through ports 21 to the cutter bearing surface.

The bushing is notched at 22 and this 5 engages a pin 23 extending down from the journal pin. This will hold the bushing against turning.

Collars 23 are interposed between the 10 cutters and the hanger and these collars are notched at 24 to engage pins 25 on the hanger.

The water for flushing passes through the ports 26 to the recess of the head for flushing the cutters.

15 The lower part of the hanger divides the recess of the head into two chambers in each of which one of the cutters is located, and the water ducts deliver water to the chambers.

20 As will be seen by an inspection of the cross sectional plan view of the head the hanger braces the walls of the head in two ways against the crushing strains to which the said walls, defining the recess, are subjected.

In one direction, the hanger by its lower portion in the form of a thick flat plate bears at its side edges at 1^a against the wall of the head and sustains the lateral thrust 30 here, and as its integral journal pins or studs bear against the inner walls of the head at the points 7^a any lateral inward thrusts or crushing strains against the walls are sustained here and as these two sets of 35 surfaces are at right angles to each other the recessed head is effectively braced by the cutter hanger member.

The hanger member with its integral journal studs and its shank provides a unitary member.

40 These studs are offset in relation to each other and their bracing effect takes place at those portions of the wall of the head adjacent the mouths of the openings, in which the cutters are located.

45 It will be noted that the structure is free from screw threaded journals or other like parts and that the assembly can be quickly made. The cutters can be simply slipped onto their journal pins together with their washers and bushings and then the whole cutter organization is simply slipped into place within the recess of the head. No special fastening devices for the cutters is 50 necessary and they can be quickly replaced when the hanger is removed by simply slipping the used one off and the new one onto the journal pin after the hanger is removed from the head.

60 The headed journal pins also serve to resist outward stresses to which the jaws 1' 1" may be subjected so that the lower part of the hanger acts as a tie piece between these jaws.

65 Contributing to the bracing effect too is

the bushing and collar arrangement of the cutter organization, wherein the bushing bears on the collars and the collars in turn bear on the central plate portion of the hanger and on the inner sides of the jaws 70 of the head.

It will be observed also that the plate portion of the hangers is arranged centrally of the head, and that the openings for the protrusion of the cutters are arranged offset in 75 relation to each other and on opposite sides of the plate. The rotary cutters have toothed cutting edges.

I claim as my invention:

1. In combination, a deep well drill head 80 having a recess in its lower face, and a hollow shank for attachment to the part from which it is suspended, a hanger having a shank extending up through the shank of the head and having a nut at its upper end bearing on the top of the shank of the head and cutters carried by the hanger and protruding beyond the head, substantially as described.

2. In combination, a deep well drill head 90 having a recess in its lower face, and a hollow shank for attachment to the part from which it is suspended, a hanger having a shank extending up through the shank of the head and having a nut at its upper end bearing on the top of the shank of the head and cutters carried by the hanger and protruding beyond the head, a lubricator supply port extending through the shank of the head to lead oil to the bore in which the shank of the hanger is located, said hanger having a conduit communicating with the bore of said drill head shank to lead the lubricant to the bearings of the cutters, substantially as described.

3. In combination, a deep well drill head 100 having a recess in its lower face with notches in its side walls opening downwardly and having a vertical bore, cutters in the recess, a hanger for the cutters having a shank 110 held in the bore of the head, and having journal means lying on its opposite sides and fitting in the downwardly open notches of the walls of the head and rotary cutters on the said journal means, substantially as described.

4. In combination, a deep well drilling head having a recess in its lower face with downwardly opening notches in its side walls, said head having a vertical bore, a 120 hanger having a shank held in said vertical bore and a plate portion extending across the recess, said plate portion having journal means lying on opposite sides thereof and carried thereby, cutters on said journal means, said journal means fitting in the downwardly open notches, substantially as described.

5. In combination, a deep well drilling head having a recess in its lower face and 130

- having downwardly open notches in its walls, a hanger in the recess comprising a plate extending across the recess, said hanger having a shank retained in the head, and having 5 notches, and having heads countersunk in the outer walls of the jaws whereby said jaws are tied together, substantially as described.
- 5 also journal means on its opposite sides with cutters thereon and bushings on the journal means and within the cutters serving to brace the substantially opposite parts of the wall of the head from the central hanger, 10 said journal means engaging the downwardly opening notches, substantially as described.
6. In combination, a deep well drilling head having a recess in its lower face and 15 having downwardly open notches in its walls, a hanger in the recess comprising a plate extending across the recess, said hanger having a shank retained in the head, and having also journal means on its opposite 20 sides with cutters thereon, collars on the journal means and bushings within the cutters serving to brace the substantially opposite parts of the wall of the head from the central hanger, said journal means engaging 25 the downwardly opening notches, substantially as described.
7. In combination with a deep well drill head having a recess in its lower face and lateral openings through its wall, forming 30 jaws, a hanger consisting of a plate extending from jaw to jaw and bearing on the inner surface thereof adjacent said openings, said hanger having journal pins offset in relation to each other and extending from 35 opposite sides of the plate, said journal pins bearing at their ends upon the inner sides of the jaws of the head, and having reduced extensions bearing in notches in the head and roller cutters on the journal pins protruding through said lateral openings. 40
8. In combination, a deep well drilling head recessed in its lower face and having lateral openings offset in relation to each other for the protrusion of cutters and 45 forming jaws, a hanger in the form of a plate arranged centrally of the recess and bearing on the opposite parts of the wall of the said recessed head and adjacent said lateral openings and carrying journals for rotary cutters on each side of the plate, rotary cutters mounted on said journals, the 50 jaws of the head being braced through the intermediary of the said hanger, substantially as described.
9. In combination, a deep well drilling head having a recess in its lower face with downwardly opening notches in its side walls, said head having a shank with a vertical bore, a hanger having a shank held in 55 said vertical bore and a plate portion extending across the recess, said plate portion having journal means lying on opposite sides thereof and carried thereby, cutters on said journal means, extensions of said journal means fitting in the downwardly open 60 notches, and having heads countersunk in the outer walls of the jaws whereby said jaws are tied together, substantially as described.
10. In combination, a deep well drill head 70 having a recess in its lower face and lateral openings for the protrusion of rotary cutters, a hanger consisting of a plate having offset integral journal pins, one on each side thereof, a rotary cutter on each pin between the plate of the hanger and the jaw of the head, said journal pins fitting in notches in the jaws of the head, substantially as described.
11. In combination, a deep well drill head 80 having a recess at its lower face and lateral openings offset in relation to each other, a hanger plate arranged centrally of the recess and bearing on the inner wall of the head adjacent said openings, said hanger 85 plate having journals on its opposite sides offset in relation to each other, bushings on the journal pins serving to brace the walls of the recess, rotary cutters on the bushings, said journal pins being seated in notches in 90 the wall of the head.
12. In combination, a deep well drill head having a recess at its lower face and lateral openings offset in relation to each other, a hanger plate arranged centrally of the recess and bearing on the inner wall of the head adjacent said openings, said hanger 95 plate having journals on its opposite sides offset in relation to each other, bushings and washers on the journal pins serving to brace 100 the walls of the recess, rotary cutters on the bushings, said journal pins being seated in notches in the wall of the head.
13. In combination, a deep well drill head having a recess in its lower face, and having a bore, a hanger having a shank held removably in the bore of the head, and having also a portion extending across the recess of the head, journal means carried by 105 said hanger and rotary cutters on said journal means and at opposite sides of said hanger, said head having downwardly opening notches in its wall receiving the said journal means, substantially as described.
14. In combination, a deep well drill head 110 having a recess in its lower face, and having a bore, a hanger having a shank held removably in the bore of the head, and having also a portion extending across the recess of the head, journal means carried by said hanger and rotary cutters on said journal means and at opposite sides of said hanger, said head having downwardly opening notches in 115 its wall receiving the said journal means, said journal means having heads countersunk in recesses adjacent said notches, substantially as described.
15. In combination in deep well drilling apparatus, a head having a recess in its lower end, with downwardly open notches in 120
- 125
- 130

- the walls thereof, a hanger having a shank portion retained in the head and a strut portion extending across the recess, journal means carried by said strut portion, rotary cutter means on the journal means, said journal means having extensions into the open notches, said rotary cutters lying between the strut portion and the walls of the recess, substantially as described.
16. In combination in a deep well drilling apparatus, a head having a recess in its lower end, with downwardly open notches

in its walls, a hanger suspended in the head and having a strut portion extending across the recess, and a rotary cutter organization supported by said strut portion and serving to brace the walls of the recess in a plane at right angles to the strut, said cutter organization having journal extensions projecting into the open notches, substantially as described. 15 20

In testimony whereof, I affix my signature.

CLARENCE E. REED.
